UNITED STATES PATENT OFFICE.

HUGH M. WAGNER, OF DUNLAP, TENNESSEE.

SELF-SERVING GASOLINE PUMP.

Application filed September 14, 1926. Serial No. 135,339.

The present invention relates to a self-serving gasoline pump and has for its object to provide a structure whereby a person may drop a coin therein such as a half dollar and pump a half dollar's worth of gasoline into a visible measuring receptacle from which he may take the gasoline through the usual hose into his tank. This structure does away with the usual attendant and is particularly useful at night in small towns and the like.

Another very important object of the invention lies in the provision of a device of this nature which may be adjusted to compensate for the varying price of gasoline.

A still further important object of the invention lies in the provision of a mechanism of this nature which is simple in its construction, comparatively inexpensive to manufacture, easy to manipulate, efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a perspective view of a pump equipped with my improved mechanism.

Figure 2 is a vertical section through the mechanism.

Figures 3 and 4 are detail sections taken substantially on the lines 3-3 and 4-4, respectively, of Figure 2.

Figure 5 is a side elevation of a casting.

Figure 6 is an edge elevation thereof.

Figure 7 is a top plan view thereof.

Figure 8 is a side elevation of the actuating rod.

Figure 9 is an edge elevation thereof.

Figure 10 an end view thereof.

Referring to the drawings in detail it will be seen that 5 denotes a base having a column 6 rising therefrom which supports the visible measuring receptacle 7 from which leads the usual hose 8 controlled by a valve 9. A second column 10 rises from the base 5 and supports a casting C. This casting C includes a base 11 having a recess 12 into which the upper end of the column 10 is threaded or otherwise secured. The base is provided with an opening 14 registering with the column 10. A projection 15 extends into the opening from the base at one end thereof. The base is provided with an annular groove 16 and a casing 17 is mounted on the base to house the remaining portions of the casting and the lower portion of the casing is provided with a flange secured in the groove in any suitable and permanent manner. The casting C further includes a riser 18 which is recessed in its bottom portion as at 19 and is formed with a groove 20 in one side and a groove 21 in the other side. The groove 21 communicates with the recess 19. Bearings 23 are formed in the riser on opposite sides of the recess 19 and has journaled therein a shaft 24 which extends through one end of the casing and has a crank 25 thereon. A gear 26 is keyed on the shaft 24. A spring-pressed pawl 27 is associated with the gear 26 to permit rotation thereof in one direction only. A pump actuating rod 28 is formed with rack piece 29 on the upper portion of one side edge and on the other side edge is provided with a longitudinally extending groove 30. A pin 31 is mounted transversely of the upper end of the rod 28 and has rollers 32 thereon. A spring 34 is fixed to the base 11 in any suitable manner and normally urges the upper end of the rod 28 in mesh with the gear 26 when said rod is in its lowermost position. Flanges 35 are formed on the ends of the sides of the groove 21 and project toward each other for forming tracks to guide the rollers 32 so as to maintain the piece 29 in mesh with the gear 26. A coin chute 36 leads from a slot 37 in the casing and extends downwardly therefrom terminating in branches 38 and 39. The branch 38 has therein a magnet 40 for attracting spurious coins. The branch 39 terminates adjacent the upper end of the rod 28 when it is in its downmost position. Thus when a coin is dropped through the slot 37 it will roll down the chute 36 and if it is the proper coin it will pass through the branch 39 and take the position shown in dotted lines in Figure 2. When the coin is in this position it will be seen that it will maintain the rod 28 with its teeth 29 in mesh with the gear 26 as the crank 25 is being rotated so that said rod will be lifted for actuating the well known pump mechanism. As the rod 28 moves upwardly the groove 30 therein will come opposite the coin and allow the same to fall down out of its active

position. Of course, any suitable receptacle may be provided for catching the coin. Any spurious coin which may be inserted into the chute 36 will be attracted by the magnet 40 and shunted through the branch 38 out to the exterior of the casing.

As the rod 28 moves upwardly and comes to the end of the flanges 35 it will be forced out of mesh with the gear 26 so as to fall 10 down into its original position, the spring 34 greatly aiding in this operation as will be apparent. A member 45 is pivoted at 46 and when in the full line position shown in Figure 2 it will engage the rod 28 to each 15 side of the groove 30 and maintain the rod 28 in mesh with the gear 26 without the necessity of inserting a coin. As the rod moves upwardly the side having the groove will slightly swing the member 45, but the 20 end 47 of the spring 34 will return the member 45 to its initial position when the rod 28 falls down. However, this member 45 is normally disposed in the dotted line position shown in Figure 2.

25 A member 48 is slideable over the upper portion of the riser 18 and has flanges 49 to form extensions of flanges 35. This member 48 is provided with a block 50 adapted to move in the groove 20. A set screw 51 is 30 threaded through the back of the member 48 and through the block for engaging the bottom of the groove 20 in order that the member 48 may be held in different adjusted positions. It will thus be seen that the 35 rollers 32 must pass up over the flanges 49 before the rod 28 is returned so that this member 48 may be adjusted up and down to compensate for the different price of gasoline which changes from time to time. Ac- 40 ccess may be had to the member 48 through a suitable door 53. The downward move- 45 ment of the rod 28 is limited by a stop pro- jection 54 provided on the riser and engage- able by one of the rollers 32 as is illustrated in Figure 5. As the rod 28 moves upwardly, it will be seen that the projection 15 will be disposed in the groove 30 and will steady the rod as it falls downwardly.

It is thought that the construction, oper- 50 ation, and advantages of this invention will now be apparent from the detailed description of the parts. If the crank 25 is turned without the proper coin being inserted into the chute 36 it will be seen that the teeth 29 55 will immediately come out of mesh with the gear so that the rod 28 will not be moved upwardly to any effective length so that no unauthorized gasoline can be taken from the pumping mechanism. When the proper 60 coin, however, has been inserted, it will be seen that this coin will maintain the upper end of the rod 28 in mesh with the gear so that as the gear turns the rod will move up- 65 wardly and when the coin comes into the groove 30 it will fall down and the rollers

32 will engage the flanges 35 and said flanges 35 will maintain the teeth 29 in mesh with the gear. As the rod moves up farther the rollers 32 will engage with the flanges 49 until they come to the upper ends thereof. 70

At this point the rollers will be forced over the ends of the flanges 49 so that the rod will gravitate downwardly of its own weight. When the rod 28 reaches its uppermost point the projection 15 is disposed in the groove 75 30 and steady the rod along with the spring 34 which is also in this groove.

The present embodiment of my invention has been disclosed in detail merely by way of example since in actual practice it attains 80 the features of advantage enumerated as desirable in the statement of the invention and the above description. It will be apparent that numerous changes in the details of construction, and in the combination and arrangement of parts may be resorted to without departing from the spirit or scope of the invention as hereinafter claimed or sacrific- 85 ing any of its advantages.

Having thus described my invention, what 90 I claim as new is:—

1. In combination, a casing, a casting in the casing, said casting having an opening, a rack rod slideable through the opening, a shaft journaled in the casting; a gear on the shaft with which the rack rod is adapted to mesh, a spring impinging against the rack rod for urging the same into mesh with the gear, coin control means for holding the upper end of the rack rod in mesh with the gear, and flanges on the casting for holding the rack rod in mesh with the gear after it has moved a distance. 95

2. In combination, a casing, a casting in the casing, said casting having an opening, a rack rod slideable through the opening, a shaft journaled in the casting, a gear on the shaft with which the rack rod is adapted to mesh, a spring impinging against the rack rod for urging the same into mesh with the gear, coin control means for holding the upper end of the rack rod in mesh with the gear, flanges on the casting for holding the rack rod in mesh with the gear after it has moved a distance, and means for lengthening 100 the flanges. 110

3. In combination, a casing, a casting in the casing, said casting having an opening, a rack rod slideable through the opening, a shaft journaled in the casting, a gear on the shaft with which the rack rod is adapted to mesh, a spring impinging against the rack rod for urging the same into mesh with the gear, coin control means for holding the upper end of the rack rod in mesh with the gear, flanges on the casting for holding the rack rod in mesh with the gear after it has moved a distance, means for lengthening the flanges, said rack rod being provided with a groove longitudinally thereof, and a pro- 115 120 125 130

jection in said opening adapted to extend in said groove as the rod moves on its stroke.

4. In combination, a casting formed with a base and a riser, said base having an opening with a projection therein, said riser having a groove on one side and a groove on the other side and a recess in its bottom portion communicating with the first groove, a shaft journaled through the casting to extend through the recess, a gear on said shaft, a spring-pressed dog associated with the gear for allowing rotation in one direction only, a rack rod movable through the opening, rollers on the upper end of the rack rod, flanges on said riser in said first groove for engaging said roller as the rack rod moves a distance upwardly to maintain said rack rod in mesh with said gear, coin control means associated with the rack rod for initially holding the same in engagement with said gear, and means on the riser for lengthening the flanges.
5. In combination, a casting formed with a base and a riser, said base having an opening with a projection therein, said riser having a groove on one side and a groove on the other side and a recess in its bottom portion communicating with the first groove, a shaft journaled through the casting to extend through the recess, a gear on said shaft, a spring-pressed dog associated with the gear for allowing rotation in one direction only, a rack rod movable through the opening, rollers on the upper end of the rack rod, flanges on said riser in said first groove for engaging said roller as the rack rod moves

a distance upwardly to maintain said rack rod in mesh with said gear, coin control means associated with the rack rod for initially holding the same in engagement with said gear, a member disposed about the upper portion of the riser and slidably thereon and including a block slidable in the second groove, a set screw threaded through the member and through the block to engage in the bottom of the groove to hold the member in different adjusted positions, said member being provided with flanges to form extensions of the first mentioned flanges.

6. In combination, a rack rod, a gear, a supporting structure for the gear, means for journaling the gear in the supporting structure, spring means urging the rack rod into mesh with the gear, coin-control means for holding the upper end of the rack rod in mesh with the gear, and flanges on the supporting structure for holding the rack rod in mesh with the gear after it has moved a distance.

7. In combination, a rack rod, a gear, a supporting structure for the gear, means for journaling the gear in the supporting structure, spring means urging the rack rod into mesh with the gear, coin-control means for holding the upper end of the rack rod in mesh with the gear, flanges on the supporting structure for holding the rack rod in mesh with the gear after it has moved a distance, and means for lengthening the flanges.

In testimony whereof I affix my signature.
HUGH M. WAGNER.
